UNITED STATES PATENT OFFICE.

WILLIAM WARREN DEAN, OF STAMFORD, CONNECTICUT, ASSIGNOR TO SPLITDORF ELECTRICAL COMPANY, OF NEWARK, NEW JERSEY, A CORPORATION OF NEW JERSEY.

MAGNETO-ELECTRIC MACHINE.

1,268,689.

Specification of Letters Patent. Patented June 4, 1918.

Application filed August 24, 1916. Serial No. 116,665.

To all whom it may concern:

Be it known that I, WILLIAM W. DEAN, a citizen of the United States, residing at Stamford, in the county of Fairfield and State of Connecticut, have invented certain new and useful Improvements in Magneto-Electric Machines, of which the following is a specification, reference being had to the accompanying drawing.

10 My invention relates to new and useful improvements in magneto electric machines for ignition purposes and also to that class of magnetos which are often used for ignition and lighting.

15 An object of the invention is to provide a magneto of the above type wherein the rotor may be formed of one piece of tubular steel having cut-away portions forming spaced prongs or arms serving as the poles

20 of the magnet.

A further object of the invention is to provide a magneto of the above character wherein the cylindrical rotor is mounted on a shaft, the endwise position of which may 25 be adjusted to bring the rotor into proper coöperative relation with the current generating coils which are carried by fixed cores.

A still further object of the invention is to provide a means for supporting the generating coils which permits a limited adjustment of the same about the axis of the shaft carrying the rotor.

These and other objects will in part be obvious and will in part be hereinafter more 35 fully described.

In the drawings which show by way of illustration one embodiment of my invention:—

40 Figure 1 is a vertical and longitudinal sectional view through a magneto having my improvements;

Fig. 2 is a sectional view on the line $a-a$ of Fig. 1; and

45 Fig. 3 is a perspective view of one of the laminations used in making up the cores.

The invention consists broadly in a generator or magneto having a suitable supporting base provided with uprights or standards, one of which is preferably formed 50 of non-magnetic material. Mounted in said uprights is a rotor, which, as shown is formed from one piece of tubular steel having cut-away portions forming spaced prongs serving as the poles of the magnet.

55 This magnet is mounted on the shaft sup-

ported in the uprights and the shaft is parallel with the prongs of the magnet. The inner ends of these prongs are magnetically connected while the outer ends of prongs are secured to a non-magnetic block to which 60 is attached one part of the shaft of the rotor. This non-magnetic block is located back from the ends of the prongs so that a space is formed between the shaft supporting the rotor and the inner face of these prongs. 65 Located in this space is a series of current generating coils. These coils are carried by cores which are connected together and mounted on the non-magnetic upright so that the coils and cores may be angularly 70 adjusted about the axis of the rotor.

Referring more in detail to the drawings, my improved magneto consists of a supporting base 1 preferably formed of cast iron. This supporting base has formed integral 75 therewith a supporting standard 2. Also mounted on the base 1 is a standard 3 which is formed of non-magnetic material. This standard is secured to the base by a bolt 3^a. The rotor as above noted is in the form of 80 a permanent magnet and preferably constructed from one piece of tubular steel having cutaway portions 4 forming space prongs 5, 6, 7 and 8. The cutaway portions 4 extend only part way throughout the 85 length of said tubular portion and therefore, the prongs are magnetically connected at their outer ends. The inner end of this tubular portion is secured to a shaft 9 by any suitable means. Located within said tubular portion adjacent to the free ends of the prongs is a non-magnetic block 10. Said block is secured to the prongs by suitable screws 11. A shaft 12 is formed integral 90 with or otherwise secured to this block 10. Said shaft 12 has a bearing in the upright 3. The shafts 9 and 12 really form a single shaft and will be so referred to hereinafter. The block 10 is secured to the prongs 5, 6, 95 7 and 8 at a point back from their free ends, which forms a space in which is located the cores 13, 14, 15 and 16 of the stationary current generating coils 17, 18, 19 and 20 respectively. These cores are made up of a group of laminations one of which is indicated at 21 in Fig. 3 of the drawing. Each lamination has a plurality of projecting portions 22 and at the ends of these projecting portions there are laterally extended parts 23 and 24. The outer face of these 100 105 110

extended parts is curved 25 to correspond to the inner curved surface 26 of the projecting prongs 5, 6, 7 and 8. The projecting portions 22 extend through the coils and the laterally extended parts 23 and 24 form the pole pieces which receive the flux from the poles of the rotor. The group of laminations is secured together by suitable bolts 27 and these bolts clamp these laminations to a supporting bracket 28. Said bracket 28 is tubular in form and surrounds the shaft 12. The bracket is also provided with a flange 29 which is formed with a series of slots 30. These slots are curved about the axis of the shaft as a center. Screws 31 pass through the slots 30 and secure the bracket to the upright 3. These slots permit of a limited adjustment of the cores and the coils angularly about the axis of the rotor.

20 A screw 32 extends through the upright and bears against the end of the shaft 12. This screw determines the endwise position of the rotor. A lock nut 33 serves to lock the screw in adjusted positions.

25 From the above description it will be apparent that I have provided a magneto wherein the rotor is a multipolar permanent magnet and the shaft which supports the rotor so that it may be either rotated or oscillated is parallel with the prongs or poles of the magnet forming the rotor. The poles of the rotor overlie stationary cores, each of which is provided with a current generating coil and these cores and coils may be angularly adjusted about the axis of the rotor. Any suitable mechanism may be used for taking the current generated in the coils and I have therefore neither shown or described such mechanism. It will be understood that one of said coils may be used for ignition purposes while another is used for lighting or other purposes.

It is obvious that minor changes in the details of construction and the arrangement of the parts may be made without departing from the spirit of the invention as set forth in the appended claims.

Having thus described my invention, what I claim as new and desire to secure by Letters Patent, is:—

50 1. A magneto electric machine comprising a multipolar permanent magnet rotor the

body portion of which is formed from an integral steel cylinder cut-away to provide parallel projecting prongs serving as the poles of the rotor and a plurality of stationary current generating coils disposed within the path of travel of the prongs.

2. A magneto electric machine comprising a multipolar permanent magnet rotor the body portion of which is formed from an integral steel cylinder cut-away to provide parallel projecting prongs serving as the poles of the rotor and a plurality of stationary current generating coils disposed within the path of travel of the prongs, a non-magnetic block fitting within and secured to said prongs and carrying one end of the shaft for the rotor.

3. A magneto electric machine comprising a multipolar permanent magnet rotor having a plurality of projecting prongs parallel with the axis of the rotor, a plurality of stationary current generating coils disposed within the path of travel of the prongs of the rotor, a shaft for said rotor, supporting brackets in which said shaft rotates and means for supporting said stationary current generating coils on one of said brackets whereby the coils may be adjusted angularly about the axis of the rotor.

4. A magneto electric machine comprising a multipolar permanent magnet rotor having a plurality of projecting prongs parallel with the axis of the rotor, a plurality of stationary current generating coils disposed within the path of travel of the prongs of the rotor, a shaft for said rotor, supporting brackets in which said shaft rotates and means for supporting said stationary current generating coils on one of said brackets whereby the coils may be adjusted angularly about the axis of the rotor, and adjustable means carried by the bracket and bearing against the end of the shaft for determining the position of the rotor relative to the coils.

In testimony whereof I hereunto affix my signature in the presence of two witnesses.

WILLIAM WARREN DEAN.
